United States Patent Office.

D. S. HINES, OF BROOKLYN, NEW YORK.

Letters Patent No. 67,113, dated July 23, 1867.

IMPROVEMENT IN HYDRAULIC CRANES.

The Schedule referred to in these Letters Patent and making part of the same.

TO ALL WHOM IT MAY CONCERN:

Be it known that I, D. S. HINES, of Brooklyn, in the county of Kings, and State of New York, have invented certain new and useful improvements in Hydraulic Cranes; and I do hereby declare the following to be a full, clear, and exact description thereof, reference being had to the accompanying drawings, and to the letters and figures marked thereon. Of these drawings—

Figure 1 is a central vertical section through the cylinder, ram, mast, and jib.

Figure 2 is a side elevation,

Figure 3 is a cross-section, taken through the jib at the line z z of fig. 2, showing the construction of the brace to the jib and suspension rods, and also of the carriage.

Similar letters of reference indicate corresponding parts in the several figures.

One of my improvements consists in placing within the cylinder a metal post so constructed that it will form a guide for the ram working over it, as well as to act as a steadiment to it to more effectually prevent any springing of the ram when the latter is under the strain of a load placed on the jib, and tending to keep the lower end of the ram in line with bearings in the neck of the cylinder, and thus relieve the crane from any jerking or unsteady motion while the crane is raising a heavy load. Cranes of the class to which my improvements relate have been heretofore constructed with a shaft projecting up through the bottom of the cylinder and connected to the ram in a solid manner. This does not make so simple nor so effective a bearing, nor can the foundation be built so solid, as provision has to be made to give access to the stuffing-box in the bottom of the cylinder.

Another of my improvements consists in combining with the ram a mast, such mast having a bearing above the jib, and removable with the jib from the cylinder and ram, by means whereof I attain greater strength of parts, and a better and more convenient bearing, with a lighter construction. By using this improved construction of the ram, neither it nor the cylinder need be so large nor heavy, besides admitting of a much lighter working-pressure of water without increasing the diameter of the ram beyond the size demanded by the pressure used.

Another of my improvements consists in the employment of a device for the purpose of separating the mast and jib from the ram when it becomes necessary to renew the packing of the ram.

Another of my improvements consists in combining with the jib a brace, so arranged as to prevent the jib from "buckling," as it is termed, while it is sustaining a heavy load.

Another of my improvements consists in suitably constructing and arranging the carriage upon the jib so that such carriage will be free from any undue lateral movement or disturbance.

And another of my improvements consists in the introduction of air, under pressure, to any convenient part of the cylinder, so as to free the cylinder and pipes connected therewith from water, especially in cold weather, when the water remaining therein is liable to freeze.

To enable others to make and use my improvements, I will proceed to describe their construction and operation.

A represents the bed-plate or foundation of the crane; B, the cylinder. This cylinder is constructed with a central post, C, which is secured in the bottom in any convenient manner, and extends up to near the neck a . D is the ram, working up and down the cylinder and over this post C. The ram is hollow down to near its base, where it contracts into the shape of a throat, b, and laterally supports the post C. At the points c c c the water can pass through grooves cut in the periphery of the throat, into the interior of the ram, so that the column of water will act on the whole area of the ram at the same time. It will thus be seen that the post C acts as a steadiment to the ram in all positions of the latter, and prevents any undue strain at the throat of the cylinder, and tends to prevent any unsteady or jerking motion when the crane is heavily loaded, by keeping the parts better in line, making the friction more uniform. E is a mast, to which the beams composing the jib are attached. This mast is constructed at its lower end, where it is attached to the ram, with a conical socket, into which the top of the ram is inserted. At the top of this socket, and transversely to and through this mast, is made a slotted opening, c' , with two projections or snugs, d d' , cast on the portion of the mast through which this slotted opening passes, so as to cause it to extend out upon either side a short distance, as shown in the

detailed fig. 4, which represents a cross vertical section of a portion of the mast and ram. Through the upper surface of these snugs are inserted screws $e\ e'$, which pass into the slotted opening and bear upon a bar, f , inserted therein. The pressure exerted upon this bar by these screws (the depth of such bar being less than the depth of the slotted opening) causes the mast to separate from the ram D , forcing the conical socket up from the end of the ram therein contained. $F\ F$ are two uprights, and G is a cross-tie, containing, at the centre, a guide, g , through which the upper portion of the mast passes, thus forming a steadiment to the mast and jib. Instead of such uprights, &c., the mast can receive support in any other convenient way, according to the location where the crane is to be used. $H\ H$ are the two beams composing the jib. $I\ I$ are the suspension rods attached thereto and to the mast E . These rods, in cranes constructed with the jib formed of one beam, are extended out to the extreme end of the jib, the yoke suspending the load to the carriage being forked and travelling over and outside of the jib, the travel of the carriage being limited by the attachment of the suspension rods. By making the jib in two parts, as shown in the drawings, and suspending the weight between the two parts, I am enabled to attach the suspension rods at any suitable point in the length of the jib, and still be able to traverse the carriage the whole length of the jib. I construct this part of the crane by placing at any convenient point, say a short distance beyond the middle or centre of these beams, an intermediate brace, consisting of two uprights, $h\ h'$, one placed and secured upon the outside of each beam, and a brace, i , between them at top, the uprights of the brace being high enough to admit of the passage of the carriage underneath, and the suspension rods $I\ I$ being bolted or otherwise attached to the outside of these uprights and through the adjacent beams. These uprights may, however, be connected with the jib either in front or behind the bearings of the tension rods, and the same result obtained. Thus there is a degree of strength and amount of stiffness given to the jib not before obtained by the ordinary way of attaching and arranging the parts, while the suspension rods may be made shorter and lighter. J is the carriage, which runs upon the jib, having four wheels and a body. This body is prolonged downwards in the shape of a triangle, in the centre of which is placed the post K , containing, at a point between the beams of the jib, a friction-roller, L . This vertical friction-roller gives the carriage a steady and easy motion along the jib. M is the pipe through which water is forced into the cylinder. N is the pipe, to which I attach any suitable air-apparatus for the purpose of introducing air under pressure into the cylinder, and freeing it and the pipes, cocks, and other apparatus connected therewith from water, for the purpose before stated.

Having described my improvements, what I claim as new, and desire to secure by Letters Patent, is—

1. The combination of the cylinder and ram with an internal central support, constructed substantially as and for the purpose described.
2. The arrangement, with the cylinder and ram, of a jib, constructed with a mast, said mast being provided with a suitable guide above the jib, substantially as and for the purpose described.
3. The arrangement, in the lower part of the mast, of a device for unlocking or releasing it from the ram, substantially as described.
4. The arrangement, with the jib, of an intermediate brace, substantially as and for the purpose described.
5. The combination, with the carriage running upon the jib, of a vertical friction-roller, substantially as and for the purpose described.
6. The introduction of air under pressure at any convenient point in the cylinder, for the purpose of blowing the water out that may remain therein and in its connecting pipes after use, substantially as described.

D. S. HINES.
